UNITED STATES PATENT OFFICE

ESTHER GOLDSTEIN, OF BROOKLYN, NEW YORK

DIAPER

Application filed November 29, 1929. Serial No. 410,288.

The present invention relates to babies' diapers of the type wherein no metal or other hard fastenings are used which come in contact with the sensitive skin of a baby, and are apt to cause injury or pain even if not in direct contact with the skin. To this end the invention has for one of its objects a diaper composed of elastic closely knit fabric, preferably comprising two similar sections of such fabric which are cut to appropriate shape so as to provide when in use a lower back portion and an abdominal portion, designed along simple lines, so that when the diaper is secured in position on the body of a baby, suitable leg openings are provided. Another object of the invention is to provide a diaper such as specified wherein the sections of fabricated material have suitable hems or selvages which, except at the top of the diaper when in use, that is at the waist line, are seamed together at the side and bottom edges so that the seams extend outwardly from the fabric body, thereby providing a baby's diaper without objectionable interior seams, hems or the like. Another object of the invention is to provide a baby's diaper composed of soft fabric throughout, which stretches in all directions, so that it will conform snugly to the body of the baby in such way as not to be uncomfortable. Still another object of the invention is to do away entirely with hard fastenings of metal and to substitute in lieu thereof tapes which secure the diaper to the baby's body at the waist line and additional tapes which secure the diaper over the abdomen, some of the tapes being secured to that portion of the diaper which constitutes the front or abdominal portion and other of the tapes being secured to side flaps or wings which extend from that portion of the diaper at the back, so that said flaps or wings may be folded over from the rear onto the front portion of the diaper, the parts being so proportioned and arranged that when the diaper is properly secured onto the body, the legs of the baby project through openings formed at the sides.

These being among the objects of the present invention, the same consists of certain

features of construction and combinations of parts to be hereinafter described and then claimed with reference to the accompanying drawings illustrating a preferred embodiment of the invention, and in which:

Figure 1 is a perspective view of the improved diaper as it would appear in using position, with the tapes tied at the waist line and over the abdomen; and

Fig. 2 is a plan of the diaper as spread out flat for its entire length, the fact that the diaper is of knit goods being indicated at several places.

Referring to the drawings, the diaper is preferably composed of two sections or layers 8, 9 of closely knit cotton fabric. The fact that each of these sections or layers is knit is indicated in Figs. 1 and 2. When composed of such soft closely knit material a diaper is provided which is more or less elastic in all directions, advantage of which is taken in designing the diaper along simple lines, making the entire diaper very efficient and comfortably fitting when in use.

The two layers or sections 8, 9 are of substantially identically the same outline, being secured together in any suitable manner, so that the diaper is provided with a front abdominal portion 10 and a portion 11 which fits over the lower portion of the back of the baby, these two portions 10, 11 being respectively at opposite sides of the approximate medial transverse line of the diaper indicated by the numeral 12. Preferably the side edges of the diaper are formed with outward curves, so that the diaper gradually increases in width toward the medial line 12, thereby providing segmental side portions 13, 14, which extend from the ends of the waist line of the front portion 10 of the diaper, partially through that portion 11 of the diaper which is to go at the back, thus enabling the diaper to be fitted to the bodies of babies of somewhat different size, although it is preferred to make the improved diaper in three different sizes.

The upper edge of the front portion 10 of the diaper is provided with a selvage edge 15 extending through both the front and back sections 8, 9 of the material, and the side edges

formed by the side portions 13, 14 are seamed together at 16, the seams extending outwardly so as not to be uncomfortable to the baby. The free edge of the back portion 11 of the 5 diaper is provided also by an outwardly directed seam 17, that is to say, at the edge which when the diaper is in using position is located at the waist line.

The outer end of the back portion 11 of 10 the diaper is provided with lateral flaps or wings 18, 19, that is with flaps which extend beyond the side seams 16 of the side portions 13, 14, the seam 17 before mentioned extending along corresponding edges of said flap 15 extensions or wings 18, 19, so that the diaper is approximately straight along that edge, thereby simplifying this portion of the diaper.

For the purpose of securing the diaper to 20 the body, the same is accomplished by means of tapes, so as to avoid the necessity of using hard and more or less injurious and painful fastenings. There is a tape consisting of a 25 middle portion 20 and free end portions 21 and 22, the middle portion 20 being stitched transversely to the abdominal portion 10 at the waist line, so that the free end portions 21, 22 extend to either side. The free ends of said tape may be received in guide loops 30 23, 23, one at each side of the front, these loops being also of tape and stitched at their ends to the section or layer of fabric 8. Also secured transversely to the front portion 10 is a tape comprising a middle portion 24 and 35 free end portions 25, 26, the middle portion being stitched on as shown. It should be noted that the stitching of the tapes is to the layer of fabric 8 and not to the layer 9, so that the diaper is formed in the nature of a 40 bag which is open at the waist line, enabling it to be inverted for washing and cleaning it.

The outward edges of the flaps or wings 18, 19 are formed with seams which are extensions of the seams 16, and to said edges there 45 are secured two tapes 27, 28 which extend outwardly, and two tapes 29, 30 which also extend outwardly, the pair of tapes 27, 28 being spaced away from the pair of tapes 29, 30 for a distance approximately the same 50 as the distance between the tapes which are secured to the abdominal portion 10 of the diaper.

On referring to Fig. 1 it will be seen that 55 when the diaper shown in Fig. 2 is properly applied to the body of the baby, the back portion 11 will cover the body up to the waist line and the abdominal portion 10 will cover it also to the waist line, at the front, and that the extension flaps or wings 18, 19 will be 60 folded over the side edges of the front portion 10 and onto said front portion, the tapes securing the diaper neatly in position without discomfort, and openings for the legs being provided below the position of the flaps 65 18, 19. In securing the diaper in position,

the free tape ends 21, 22 are passed through the guide loops 23 and their terminals tied with the tapes 29, 30 into bows, which may be made more or less tight, as desired. Having 70 adjusted the diaper at the waist line, the tapes 27, 28 are tied with the free tape ends 25, 26 into suitable bows over the abdomen, thereby neatly and snugly securing the diaper in reliable position onto the body of the baby, who will feel no discomfort therefrom, and if the diaper is too tight, it is a very easy matter to loosen it up, or vice versa.

What I claim, is:

A diaper, comprising a fabricated body, 80 having side edge-portions extending toward the approximate middle line of the diaper and providing between them a back portion and an abdominal portion at opposite sides of such line, the back portion and the abdominal portion being of sufficient proportions to come to the waist-line when the diaper is in use, and the abdominal portion having a double-end tape secured intermediately of its length along the waist-line and tape-receiving loops also at the waist-line, and located beyond the point of securement of the tape, and the abdominal portion also having a double-end tape secured intermediately of its length to the abdominal portion along a line substantially parallel with aforesaid 90 tape, and the back portion having side flaps with edges which are substantially in line with the waist-line of the back portion, and the flaps each having a pair of outward tapes, 95 whereby when the diaper is in use the flaps may extend over the abdominal portion and the tapes of both portions be secured together respectively at the waist-line, at which they may pass through said loops, and over the abdomen, leaving openings below for the protrusion of the legs.

ESTHER GOLDSTEIN.
